UNITED STATES PATENT OFFICE.

HIRAM GOFF BAKER, OF MONTREAL, QUEBEC, CANADA.

DRY-PIPE VALVE.

941,971.

Specification of Letters Patent. Patented Nov. 30, 1909.

Application filed October 16, 1903. Serial No. 458,102.

To all whom it may concern:

Be it known that I, HIRAM GOFF BAKER, a citizen of the United States of America, and resident of 199 Hutchison street, in the city of Montreal, in the district of Montreal, in the Province of Quebec, in the Dominion of Canada, have invented certain new and useful Improvements in Dry-Pipe Valves; and I do hereby declare that the following is a full, clear, and exact description of the same.

The invention relates to improvements in dry pipe valves, as described in the present specification and illustrated in the accompanying drawings that form part of the same.

The invention consists essentially in the novel arrangement and construction of parts, whereby the valve, on the release of the pressure from therebehind, remains open by means of its up-set position, through its pivotal arrangement at the lower end of the valve chamber.

The objects of the invention are to provide a valve for sprinkler systems in which the danger of derangement is obviated, to improve the accuracy, and general efficiency in operation, and to cheapen the cost of production.

In the drawings, Figure 1 is a vertical sectional view of the valve chamber and valve.

Fig. 2 is a front elevation of the device showing the cover partially broken away and parts disclosed thereby in section.

Referring to the drawings, 1 is the valve chamber having the perpendicular circular front side 2 and the central ingress opening 3 and the hand hole 4 through said front side. 5 is the rear side of said chamber slanting inwardly toward the lower end of the front side and also circular in shape, said rear side being here shown as secured to the flange 6 extending inwardly from the circular side wall 7. 8 is the outlet opening in the top of said side wall 7. 9 is the drip opening from the bottom of said side wall. 10 is a hand hole through said side wall closed by the cover 11. It will be seen from the aforesaid description that the said valve chamber 1 is formed with the interior converging front and rear walls 2 and 5 respectively, the said rear wall 5 having the lugs 12 projecting inwardly therefrom and forming valve stops or rests.

13 is a circular flange extending inwardly

into proximity with the front side 2 from the side wall 7, said flange having the annular slot 14, into which is inserted a suitable valve seat 15, said valve seat projecting slightly beyond the side face of said flange.

16 is the valve having the circular surface 17 finished central portion 17 engaging the seat 18, the latter encircling the ingress opening 3, said valve extending from said central portion 17 to the flange 13, a rubber gasket 19 being shown as secured to said valve and 65 as abutting the said seat 15 in the closed position of the valve.

20 is an arm pivoted on the pin 21, the latter being secured at the extreme lower end of the valve chamber 1 and the said arm being mounted on said pin so as to allow a little play thereon, said arm at its upper end being secured to and supporting the valve 16.

22 is a lug extending outwardly from the valve 16 toward the upper end thereof. It must be understood that the valve 16 may be any suitable shape and hinged in any suitable manner at the lower end thereof so as to fall away from the opening 3 on the release of the pressure from behind said valve.

23 is a spring-held latch normally abutting the upper surface of the lug 22 and adapted to spring into position between said lug and the front side 2 on the opening of said valve 16, thus preventing the accidental closing of the valve. This latch may be arranged in any suitable way or may be omitted, if found to be an unnecessary safety device.

24 is a gate sliding in the vertical ways 25, 90 the latter being secured to the outer face of the front side 2 to each side and abutting said hand hole 4.

26 is a cylinder suitably supported from the valve chamber casing and having an inlet 27 through the top end thereof.

28 is a piston operating in the cylinder 26.

29 is a piston rod connected with the piston 28 at one end and at the other end to the gate 24.

30 is a pipe leading from the orifice 31 immediately to the outside of the ingress opening 3 and connected with said cylinder at said inlet opening 27.

32 is a valve secured to the underside of 105 the piston 28, and 33 is a valve seat at the lower end of the cylinder 26.

34 is an outlet opening at the bottom of

the cylinder 26 emptying over the drip opening 9.

In the operation of this invention, the valve, which is of the differential type, is held to engagement with the seats 18 and 15 by the air pressure therebehind, the pipes of the sprinkler system being pumped full of air as usual in such systems and the said air reaching the valve chamber through the water outlet opening 8. The pressure of the water on the valve is not sufficient ordinarily to open said valve against said air pressure but immediately a leak occurs in any of the pipes of the sprinkler system, the said pressure is released from the larger rear face of said valve, consequently the water forces the valve open, and through its own weight, and the pressure of said water, falls over on to the incline rear side of the valve chamber against the said rests or stops, leaving a free passage for the water through the valve chamber and outlet 8 into the sprinkler pipes, where it is distributed as usual.

The valve chamber may be reached at any time through the large hand hole 10 and it will be noticed that the water pressure cannot remain on while the said hand hole is open, unless the valve is manually held in its closed position.

In regard to the hand hole 4, this may be opened while the valve is in service, but must be closed on the opening of said valve and therefore the automatic arrangement of gate as herein shown, is the means by which said hand hole 4 is always kept in its closed position, until manually opened and held open during any repairs necessary to the chamber or seats on the outer side of the valve. The continuous pressure of the water on the piston in said cylinder will always retain said gate in its lower position, even if it should fail to fall at that position by reason of its own weight.

What I claim as my invention is:

1. In a dry pipe valve for sprinkler systems, a valve chamber converging from its upper end at the outside of a vertical outlet opening to the lower end and having a perpendicular front wall and an inlet opening centrally arranged in said front wall, a plurality of valve seats arranged in said chamber and a valve having corresponding surfaces meeting said seats and supported in a perpendicular position by an extension therefrom, said extension being pivoted at the lower end of said chamber and said valve being adapted to fall by gravity or the rush of water through said inlet opening to the slanting rear wall of said valve chamber and to remain in said open position and form a deflecting surface for the rush of water through said inlet opening to said outlet opening and normally to be held in its

closed perpendicular position by air pressure therebehind.

65

2. In a dry pipe valve for sprinkler systems, a valve chamber converging from the outer sides of a vertical outlet opening at the top thereof to a drip chamber at the bottom thereof and having a perpendicular front wall and an inlet opening centrally arranged in said front wall and lugs to the inside of said perpendicular front wall extending downwardly from the upper wall and upwardly from the drip chamber wall, 75 a valve seat secured in said lugs, a valve seat secured around said inlet opening, and a valve having a central finished face engaging said seat around said inlet opening, a suitable extension surface engaging the said 80 inner seat and an arm supporting the valve in a perpendicular position during its engagement with said seats, said arm being pivotally secured in said drip chamber and said valve being adapted to fall from its perpendicular position to the slanting rear wall of said chamber and form a deflecting surface for the rush of water to the outlet opening and to normally be held to its closed position by air pressure.

90

3. In a dry pipe valve for sprinkler systems, a valve chamber formed with a perpendicular front side and a sloping rear side, said sides converging toward the lower end, an outlet through the top thereof and an 95 inlet centrally arranged in said perpendicular front, a valve seat suitably secured and surrounding said inlet opening, a valve seat of larger diameter than the aforesaid seat arranged within said casing in projecting 100 parts of the top and bottom, a valve having a central surface finished face meeting the aforesaid inlet seat, and a resilient attachment meeting the inner seat, an arm hinged within said casing at the lower end thereof 105 and secured to said valve and permitting said valve to fall to said sloping side on the release of air pressure from therebehind on the in-rush of the water through the inlet to the outlet, said valve deflecting said water 110 to said outlet in the flow thereof, and automatic means for preventing the accidental closing of said valve following its release by the lessening of the pressure of air.

110

4. In a dry pipe valve for sprinkler systems, a valve chamber having a suitable hand hole in the front side thereof, water ingress and egress openings and valve seats, a valve closing said ingress openings, a gate slidably arranged over said hand hole at 120 the front side, and hydraulic means for closing said gate and retaining it in its closed position.

115

5. In a dry pipe valve for sprinkler systems, a valve chamber having a suitable 125 hand hole in the front side thereof, water

ingress and egress openings and valve seats, a valve closing said ingress openings, a gate slidably arranged over said hand hole at the front side, a cylinder suitably connected to 5 the water supply outside of said valve, a piston in said cylinder forming a valve in its lower position in said cylinder, and a rod extending from said piston to said gate.

Signed at the city and district of Montreal, in the Province of Quebec, in the Dominion of Canada, this 12th day of October, 1908.
